DESCRIPTION

USPC D13/152; D26/138
CPC . H02G 1/085; H02G 3/20; F21S 9/022; F21S

FIG. 1 is a top view of a portion of a plastic deep electrical junction box, showing our new design;
FIG. 2 is a bottom view thereof;

8/02; F21S 8/026; F21V 21/14; F21V
21/04; F21V 5/043; F21V 25/125; F21K
9/68; A01G 9/1423

FIG. 3 is a right side view thereof, the left side being identical;

FIG. 4 is a front view thereof, the rear view being identical;
FIG. 5 is a top perspective view thereof; and,

FIG. 6 is a bottom perspective view thereof.
The dash-dash broken lines in the drawings are for the purpose of illustrating portions of the plastic deep electrical junction box that form no part of the claimed design. The dot-dash-dot broken lines in the drawings are for the purpose of defining the bounds of the claimed design. Surfaces in the drawings that do not have surface shading are disclaimed.

See application file for complete search history.
